UNITED STATES PATENT OFFICE

2,220,377

CARBON PAPER HOLDER

John S. Marran, Stamford, Conn., assignor to
 The Miller-Bryant-Pierce Company, Aurora,
 Ill., a corporation of Illinois

Application July 28, 1938, Serial No. 221,691

6 Claims. (Cl. 282—29)

The invention relates generally to holders for carbon paper or the like, and more particularly to holders adapted for use in manifolding machines and the like.

5 In certain forms of manifolding machines and the like where single sheets of carbon paper are used in conjunction with a suitable holder therefor, a plurality of sheets being simultaneously used in such a machine, it has been found that there is 10 a portion of each sheet of carbon paper which cannot be used unless the same is taken out of the machine and inverted, this portion being that extending from the holder to which it is secured, to the platen of the machine, and the present 15 invention has as an important object the production of a device by means of which this waste of carbon paper is eliminated, whereby a shorter sheet of carbon may be utilized, and which is entirely used.

20 Another object of the invention is the construction of such a device which may be used over and over again with a comparatively large number of sheets of carbon paper.

25 A further object of the invention is the construction of such a device which securely holds the carbon paper and from which the same may be easily removed without tearing the paper or the like.

30 Another object of the invention is the production of such a device which is simple in construction and relatively inexpensive to manufacture.

35 Another object of the invention is the construction of such a device in which the carbon paper is always aligned on the holder, thereby insuring proper operation when used in the machine.

40 Many other objects and advantages of the construction herein shown and described will be obvious to those skilled in the art from the disclosure herein given.

45 To this end my invention consists in the novel construction, arrangement and combination of parts herein shown and described and more particularly pointed out in the claims.

In the drawing wherein like reference characters indicate like or corresponding parts:

Fig. 1 is a side elevational view illustrating the 50 holders in use and showing a portion of a typical machine upon which the same is to be used;

Fig. 2 is a plan view of the holder and sheet of carbon paper with a portion broken away to show the construction of the holder;

Fig. 3 is a side view of a holder with a sheet 55 of carbon attached thereto; and

Fig. 4 is an enlarged sectional view of the holder with a portion of the carbon paper.

Fig. 1 illustrates the device as used in one type of manifolding machine, 1 representing the 5 pages to be filled in. Interposed between the 5 pages are relatively flat rods 2 to which the ends of the carbon paper are ordinarily secured. The 10 pages and the interposed sheets of carbon are then fed past the guide plate 3 and around the platen 4. As the pages of the manifold are fed 15 past the platen 4, the sheets of carbon paper will feed along with them, and after a page has been completed, the paper release on the machine is manipulated, thereby releasing the pages, after 20 which the rods 2 are drawn away from the platen, thereby drawing the carbon paper back to its original starting position, which in this case, will then 25 position the same in the next page to be filled in. This is accomplished for example by a lever 5 20 which is connected through a suitable mechanism to the rods 2 so that operation of the lever 5 will return the carbon sheets to their original starting position. After the carbon has been 25 drawn back to the next page, the preceding completed page is removed from the machine. These 30 pages which are ordinarily formed from a continuous strip of paper are perforated at their adjoining edges so that they may readily be disconnected from one another and removed from 35 the machine. The rods 2 will approach the platen as the page is filled in, and obviously, as the rods 2 cannot pass around the platen, but will reach the limit of their travel before engaging the 40 guide plate 3, there will be a portion of the carbon paper extending from the rods 2 over the guide plate 3 and around the platen to the line of printing which will not be used unless the 45 pages are taken out of the machine and the carbon paper turned around so that the unused portion will then be the first to enter the machine. Applicant's device takes the place of the unused portion of the carbon paper and thereby eliminates wasting of the carbon paper and the necessity of turning the same around in the machine, as well as enabling the use of carbon paper 45 of a shorter length.

As shown in Figs. 2, 3, and 4, the invention 50 comprises a sheet of paper 6 or other suitable material, which may or may not be suitably colored as desired, one end 7 of which is folded back upon itself and stitched or otherwise secured at 8 to form a pocket of a size to receive a rod 2, or if desired, may be held in place on the rod 2 by suitable clips or the like. This paper may be 55

of any desired length depending on the machine in which it is to be used, the length being such as to utilize the entire piece of carbon paper 9 to which it is to be secured. The opposite edge 5 of the sheet of paper 6 is provided with a plurality of apertures 11 which are preferably of triangular shape, the apex 12 of the triangle being adjacent the free edge of the paper. Extending across each opening on one side of the 10 paper is a piece of suitable ribbon-cement adhesive, the same preferably having a paper backing 13 with the adhesive 14 adjacent the opening and also forming a means of securing the same to the paper sheet 6.

15 To use the device, the edge of the carbon paper 9 is placed over the opening 11 with the carbon 16 on the upper or outside and the paper 17 down or on the bottom side adjacent the adhesive 14 and aligned on the sheet 6 by means of the guide 20 line 15 printed on the latter. The adhesive material 14 is non-drying or hardening so that the sheet 6 may be used over and over again. To remove the sheet of carbon 9 from the sheet 6, the carbon paper is merely turned back over the sheet 25 6 and gently pulled therefrom. Due to the novel shape of the openings 11, as the carbon paper is drawn back, only a very small portion of the adhesive surface is removed at the start, the same increasing as the paper is removed therefrom.

30 Thus, it will be seen that the carbon paper will be initially removed from a very small portion of the adhesive surface, increasing as the same is drawn away therefrom. In other words, only a very small portion of the adhesive surface will resist the removal of the paper at the start, thereby preventing any tearing or the like of the carbon paper.

35

It will be seen from the above description that I have provided a novel holder for carbon paper 40 which eliminates any shifting of the same or the necessity of turning the paper around in the machine, and also allows the use of a smaller sheet of carbon than has heretofore been used in this type of machine. Likewise, I have provided novel 45 means for securing the carbon paper to the holder whereby the same may be readily removed without tearing thereof.

Having thus described my invention, it is obvious that various immaterial modifications may 50 be made in the same without departing from the spirit and scope of my invention; hence, I do not wish to be understood as limiting myself to the exact form, construction, arrangement and combination of parts herein shown and described or uses mentioned.

What I claim as new and desire to secure by Letters Patent is:

1. A carbon paper holder of the kind described comprising a sheet of paper, one end of which 60 is folded back upon itself, said paper sheet having a triangular aperture therein at the opposite end thereof, said triangular aperture having its apex pointing outwardly toward the adjacent edge of said opposite end of said sheet, and a piece of material extending across said aperture and having a coating of substantially non-drying adhesive on the face thereof adjacent said sheet.

2. A carbon paper holder of the kind described

comprising a sheet of paper, one end of which is folded back upon itself, said paper sheet having a plurality of triangular apertures therein at the opposite end thereof, said triangular apertures having their apexes pointing outwardly toward the adjacent edge of said sheet, a piece of material extending across each aperture and having a coating of substantially non-drying adhesive on the face thereof adjacent said sheet.

3. A carbon paper holder for use in manifolding machines having carbon paper engaging means thereon, said holder comprising a sheet of suitable material, one end thereof engageable with said engaging means, said sheet having a plurality of apertures therein positioned at the opposite end of said sheet, and a plurality of strips of material extending across the respective apertures, said strips having a coating of substantially non-drying adhesive on the side thereof adjacent said sheet, the distance between that portion of the sheet engageable with said means and the opposite end of said sheet being not more than the paper-travel distance from the printing line of said machine to said engaging means, when the latter is at the end of its paper feeding movement.

4. A carbon paper holder for use in manifolding machines having carbon paper engaging means thereon, said holder comprising a sheet of paper, one end of which is folded back upon itself and the extreme edge stitched thereto to form a casting engageable with said engaging means, said sheet having a plurality of triangular apertures therein positioned at the opposite end of said sheet, said triangular apertures having their apexes pointing outwardly toward the adjacent edge of said opposite end of said sheet, and a plurality of strips of material extending across the respective apertures, said strips having a coating of substantially non-drying adhesive on the side thereof adjacent said sheet, the distance between that portion of the sheet engageable with said means, and the opposite end of said sheet being not more than the paper-travel distance from the printing line of said machine to said engaging means, when the latter is at the end of its paper feeding movement.

5. A carbon paper holder of the kind described comprising a sheet of suitable material, one end of which is folded back upon itself and the extreme edge secured thereto, said sheet having an aperture therein at the opposite end thereof and substantially non-drying adhesive means extending across said aperture and engageable through the same with a sheet of carbon paper for securing the latter to said holder.

6. A carbon paper holder of the kind described comprising a sheet of suitable material, one end of which is engageable with the carbon holder of a manifolding machine or the like, said sheet having an aperture therein at the opposite end thereof and substantially non-drying adhesive means extending across said aperture and engageable through the same with a sheet of carbon paper for securing the latter to said holder.

JOHN S. MARRAN.
